BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,098,922.

Specification of Letters Patent.

Patented June 2, 1914.

Application filed May 4, 1909. Serial No. 493,908.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to the line-spacing mechanism of typewriting machines, and particularly to means for conveniently writing exponents and characters above and below the line of writing.

The platen is usually mounted for rotation and is provided with a notched line-space wheel, in which plays a spring-pressed detent or check. According to the present invention, a handle controls said detent or check, a pivotal connection being provided between the handle and the check, whereby the handle may move the check, together with the wheel, in either direction from initial position, for about half a line-space. A spring-pressed cam is preferably provided for returning the handle and check to normal positions; and stops are also provided for limiting the stroke in each direction to less than a line-space.

In the accompanying drawings, Figure 1 is a sectional end elevation of the platen frame and line-spacing wheel with my improvements applied thereto; the parts being shown in normal positions. Fig. 2 is a similar view, showing the platen turned to the right for less than a line distance, to permit a character to be written above the line of writing. Fig. 3 is a similar view, showing the platen turned to the left for a similar distance, to permit a character to be written below the line of writing. Fig. 4 is a perspective view of a pivoted cam arm for coöperation with the platen adjusting lever. Fig. 5 is a front view of the platen and its connected parts, the line-space wheel being partly broken away.

Types 1 strike upon the front of a cylindrical platen 2, which is mounted by means of an axle 3 in the ends 4 of a platen frame 5. Fixed on the axle outside of the platen frame is a line space wheel 6. An arm 7 carries at its lower end a roll 8, which is pressed by a spring 9 against the teeth of the line-space wheel, to check or detain the latter against accidental rotation. Said detent 7 has a large hub, whereby it is pivoted upon

a wrist 10, which is provided upon a lever 12 having a handle 13, said lever pivoted upon a stud 14 projecting from the platen frame end. The wrist 10 is eccentric to the stud 14, so that by turning the lever 12 60 backwardly and forwardly, the wrist and detent 7 may be carried upwardly or downwardly, as at Fig. 2 or Fig. 3. The bore for the stud 14 passes through the wrist 10; and the spring 9 is coiled around the hub 65 of the detent and bears at one end against a pin 15 projecting from the platen frame; the other end bearing against the detent itself. A nut or other keeper 16 may be provided on the stud 14 to retain the parts. 70 The lever 12 also has an arm 17, having at its end a roller stud 18 to engage a V-notch formed on a plate or arm 19, which is pivoted at 20 upon a bracket 21 secured to the platen frame ends 4. A spring 22, coiled 75 around the stud 20 and bearing at one end against a fixed pin 23 and at the other end against a pin 24 on the arm 19, causes the roller stud 18 to be held firmly to the bottom of the V-notch in said arm 19; this being 80 the normal position of the parts, as at Fig. 1.

When the handle 13 is swung backwardly, the roller stud 18 rolls down one cam edge 25 of the V-notch. Upon relieving the handle 13 from pressure, a spring 22 forces 85 the arm 19 to the right, the cam edge 25 forcing the arm 17 to rise until the stud 18 rests in the bottom of the notch. Thus the detent 7 is thrown up and the platen is thereby moved from the position at Fig. 1 to that 90 at Fig. 2, the platen turning to the right (or downwardly) for the distance between the horizontal axial plane 26 of the platen to the point indicated at 27, Fig. 2, thus permitting a character to be written a little 95 above the line of writing. Upon the release of the handle 13, the parts are returned by the spring 22 to normal positions.

When the handle is pulled forwardly to the position at Fig. 3, the roller stud 25 100 rides up along a cam edge 28 forming the other side of the V-notch, and the eccentric 10 swings downwardly and forces down the detent 7, together with the line-space wheel and platen, so that the front of the latter is 105 turned upwardly from 26 to 27, to permit a character to be written below the line of writing. Upon release of the handle 13, the spring 22 again returns the parts to initial position. It will be seen that the handle 13 110

is constantly connected to the platen, and that by a single stroke it may advance or retract the platen.

5 The cam 25 terminates in a shoulder or stop 29, and the cam 28 terminates in a stop 30, the stops limiting the movement of the line-space wheel in each direction from normal to less than the distance from one tooth to the next of the line-space wheel.

10 The invention is not limited to the employment of the spring for returning the platen to initial position from the position at Fig. 2 or at Fig. 3, or for holding the parts in their normal positions.

15 Having thus described my invention, I claim:

1. In a typewriting machine, the combination with a platen and a line-space wheel, of a lever having an eccentric wrist, a detent 20 pivoted on said wrist and pressed by a spring against the teeth of said line-space wheel, said lever provided with a handle and movable in opposite directions from normal position, and means to hold said lever in normal position.

25 2. In a typewriting machine, the combination with a platen and a line-space wheel, of a lever having an eccentric wrist, a detent pivoted on said wrist and pressed by a 30 spring against the teeth of said line-space wheel, said lever provided with a handle and movable in opposite directions from normal position, means to hold said lever in normal position, and means to determine 35 the length of stroke of said lever in opposite directions away from normal position.

3. In a typewriting machine, the combination with a platen, a platen frame and a line-space wheel, of a lever pivoted upon the 40 platen frame and having a handle and an arm, and also provided with an eccentric wrist, a detent pivoted on said wrist and pressed by a spring against the teeth of said line-space wheel, a pivoted cam-plate or de- 45 tent to engage a stud provided upon said arm, and a spring to enable the cam plate to co-operate with said arm to return the latter and said detent to a normal midway position.

50 4. In a typewriting machine, the combination with a platen, a platen frame and a line-space wheel, of a lever pivoted upon the platen frame and having a handle and an arm, and also provided with an eccentric 55 wrist, a detent pivoted on said wrist and pressed by a spring against the teeth of said line-space wheel, a pivoted cam-plate or de- 60 tent to engage a wrist provided upon said arm, a spring to enable the cam plate to co-operate with said arm to return the latter and said detent to a normal midway position, and stops to limit the strokes of said arm away from normal position.

5. The combination of a revolute platen, 65 a device for determining the extent of line-

spacing movement thereof, a finger-piece operatively connected to said device for shifting said device and with it the platen either forwardly or backwardly less than a line-space in either direction from a central 70 normal position, and spring actuated means for returning said device to initial position together with the platen.

6. In a typewriting machine, the combination with a platen and a line-space wheel, of a detent pressed by a spring against the teeth of said wheel, a member having a finger-piece and to which said detent is pivoted, and means to hold said member and detent in normal positions, said member 80 movable in opposite directions from normal position to shift said detent and rotate said wheel in opposite directions to bring the printing line either above or below its normal position.

85 7. In a typewriting machine, the combination with a platen and a line-space wheel, of a spring-pressed detent constantly engaging said line-space wheel, said detent mounted to yield to permit rotation of the platen independently thereof, a handle, means for enabling said handle to move said detent together with said line-space wheel forwardly and backwardly, stops to limit the strokes of the detent and line-space wheel to less than a 90 line-space in either direction from a central normal position, and means mechanically determining the normal central position of the detent.

90 8. The combination with a platen, of a toothed wheel connected to the platen, a lever pivoted eccentrically of the platen, said lever being capable only of turning movement about its pivot, and being movable on said pivot only in either one of two directions from normal central position, means operated by such movement of the lever to turn the said wheel and platen in the direction of movement of the lever, and means to return the lever to normal central position and to return said wheel and platen with said lever and hold said parts in returned position.

100 9. The combination with a platen, of a toothed line-space wheel connected thereto, a finger piece, means to hold said finger piece in normal position, said finger piece mounted for movement in a single plane only, and movable in said plane either forwardly or backwardly from normal position, and means operated by such movement of the finger piece to turn the wheel and platen either forwardly or backwardly to displace the printing line on the platen either above or below its normal position, and to return the 105 said wheel and platen to restore the printing line to normal position when the finger piece is returned to normal position.

110 10. The combination with a platen, of a toothed line-space wheel connected thereto,

- a finger piece, means to hold said finger piece in normal position, said finger piece mounted for movement in a single plane only, and movable in said plane either forwardly or backwardly from normal position, means operated by such movement of the finger piece to turn the wheel and platen either forwardly or backwardly to displace the printing line on the platen either above or below its normal position, and means to return said finger piece to normal position together with said wheel and platen.
11. The combination with a platen, of a toothed line-space wheel connected thereto, a finger piece, said finger piece mounted for movement in a single plane, and movable in said plane either forwardly or backwardly from normal position by pressure applied thereto, means to hold said finger piece in normal position and to return it to normal position after it has been moved in either direction, a spring held detent engaging said wheel and connected to said finger piece to be moved thereby to rotate the platen either forwardly or backwardly to displace the printing line either above or below its normal position, and means to return the finger piece to normal position together with the wheel and platen.
- 15
- 20

either forwardly or backwardly to displace 25 the printing line either above or below its normal position.

12. The combination with a platen, of a toothed line-space wheel connected thereto, a finger piece, said finger piece mounted for 30 movement in a single plane, and movable in said plane either forwardly or backwardly from normal position by pressure applied thereto, means to hold said finger piece in normal position and to return it to normal 35 position after it has been moved in either direction, a spring held detent engaging said wheel and connected to said finger piece to be moved thereby to rotate the platen either forwardly or backwardly to 40 displace the printing line either above or below its normal position, and means to return the finger piece to normal position together with the wheel and platen.
